C. F. STEWART.
CIGARETTE MOLDING DEVICE.
APPLICATION FILED JAN. 30, 1913.

1,084,374.

Patented Jan. 18, 1914.

UNITED STATES PATENT OFFICE.

CHARLES F. STEWART, OF FLINT, MICHIGAN.

CIGARETTE-MOLDING DEVICE.

1,084,374.

Specification of Letters Patent. Patented Jan. 13, 1914.

Application filed January 30, 1913. Serial No. 745,222.

To all whom it may concern:

Be it known that I, CHARLES F. STEWART, a citizen of the United States, residing at Flint, in the county of Genesee, State of Michigan, have invented certain new and useful Improvements in Cigarette-Molding Devices; and I do hereby declare the following to be a full, clear, and exact description of the invention, such as will enable others skilled in the art to which it appertains to make and use the same.

This invention relates to improvements in cigarette molding devices.

One object of the invention is to provide a simple device of this character which may be carried conveniently in the pocket.

Another object is to provide a device of simple construction, of this character, and with which cigarettes can be quickly and easily made.

Other objects and advantages will be apparent from the following description when taken in connection with the accompanying drawings.

In the drawings Figure 1 is an elevation of the tobacco containing receptacle, Fig. 2 is an elevation of the mold, Fig. 3 is a sectional view through the tobacco container, showing the method of extracting tobacco therefrom, and Fig. 4 is a sectional view showing the manner in which the cigarette is finally made.

Referring particularly to the accompanying drawings, 10 represents a receptacle, formed preferably of metal, and flat for convenience in carrying in the pocket, this receptacle being adapted to contain tobacco. Secured in one of the end walls of the container 10 is a metal tube 11, the major portion of which projects from the end of the container when in operation, the outer end being provided with the stop flange 12 to limit the movement of the same when the said tube is pushed inwardly preparatory to placing the box in the pocket. Secured to the opposite end wall of the container and projecting to a point below the tube 11 is a stem or rod 13, the purpose of which will appear in the description of operation which will follow. The box is formed with a suitable hinged lid 14.

For molding the cigarettes, I provide a metal tube 15 which will be approximately

the size it is intended to make the cigarette. One end of this tube has a centrally perforated wall 16, through which projects the stem 17, the outer end of which is provided with a button 18, and the inner end with a plunger head 19, this plunger head being adapted for forcing the tobacco from the tube upon pressure being applied on the button 18.

In the operation of the device, the tube 12 is withdrawn to the proper distance, after which the open end of the tube 15 is inserted within the tube 12 so that the stem 13 is disposed therewithin. The receptacle 10 is inverted, and the tube 15 moved inwardly and outwardly through the tube 12 until the said tube 15 is filled with tobacco. The tube 15 is then removed and a suitable cigarette paper wrapped around the tube and properly sealed, the paper being then slipped a short distance off the open end of said tube and twisted to close the end. The stem 17 is then pushed inwardly to force the tobacco into the paper tube and at the same time force the paper off of the tube 15. The paper and tobacco which is forced off of the tube 15 constitutes the completed cigarette. The tube 12 is provided as a guide for the tube 15 so that when said tube 15 is inserted into the box, the stem 13 will always enter the inner end of the tube. If desired this tube 12 may be rigidly mounted, but I prefer to mount the same slidably, so that it can be pushed in when the box is to be placed in the pocket.

When the device is placed in the pocket, the tube 15 can be inserted in the tube 12, a stop flange 20 being provided at the closed end of the tube 15 to prevent the same from going into the container 10. It will be noted that as the tube 15 is moved inwardly and outwardly of the container 10, the stem 13 guides the said tube 15, and assists in packing the tobacco in the said tube and loosening the same within the container.

What is claimed is:

A cigarette making device, including a tobacco container comprising a sliding tube mounted in one end, a stem secured within the container and extending to a point adjacent the inner end of the said tube, and a molding device comprising a tube open at one end and provided with a perforated

wall at the opposite end, a plunger rod slideable through the opening, a plunger head on the inner end of the stem, a button on the outer end, and a stop flange on the closed 5 end of said tube whereby the tube may be inserted within the tube of the container, when the device is to be placed in the pocket.

In testimony whereof, I affix my signature, in the presence of two witnesses.

CHARLES F. STEWART.

Witnesses:

CLIFFORD W. BISHOP,
N. A. DUNHAM.
